Primary Examiner — Rosemary K Tarcza(74) *Attorney, Agent, or Firm* — Tarter Krinsky & Drogin LLP(57) **CLAIM**

The ornamental design for a battery starter, as shown and described.

DESCRIPTION

FIG. 1 is a front view of a first embodiment of a battery starter;
FIG. 2 is a rear view thereof;
FIG. 3 is a right view thereof;
FIG. 4 is a left view thereof;
FIG. 5 is a top view thereof;
FIG. 6 is a bottom view thereof;
FIG. 7 is a front perspective view thereof;
FIG. 8 is a rear perspective view thereof;
FIG. 9 is a front view of a second embodiment of a battery starter;
FIG. 10 is a rear view thereof;
FIG. 11 is a right view thereof;
FIG. 12 is a left view thereof;
FIG. 13 is a top view thereof;
FIG. 14 is a bottom view thereof;
FIG. 15 is a front perspective view thereof; and,
FIG. 16 is a rear perspective view thereof.

The phantom lines shown in the drawings are for illustrative purposes only and form no part of the claimed design.
